UNITED STATES PATENT OFFICE.

WILLIAM E. McLAUGHLIN, OF MIDDLETOWN, OHIO, ASSIGNOR TO THE BARKELEW ELECTRIC MANUFACTURING COMPANY, OF MIDDLETOWN, OHIO, A CORPORATION OF OHIO.

DIMMING APPARATUS.

Application filed November 25, 1925. Serial No. 71,309.

My invention relates to a dimming apparatus and, in particular, to an apparatus to be installed on cars employing two filament bulbs or separate dimming bulbs without a resistance.

It is the object of my invention to provide a switch which may be applied to existing cars or which may be originally applied on automobiles as factory equipment, 10 which may be used on cars which do not have a resistance in their main switch or elsewhere but which employ for dimming purposes bulbs with two filaments or two separate bulbs.

15 It is a further object to provide a switch and wiring which can be readily attached to the existing electrical equipment of a car and which can be operated by the foot of the operator, as his hands are already 20 fully employed.

In the accompanying drawings:

Figure 1 is an elevation of the switch installed on a floor board with the floor board and cover of the switch shown in 25 section, the side walls of the cover being removed;

Figure 2 is a section on the line 2—2 of Figure 1;

Figure 3 is a section on the line 3—3 of 30 Figure 1;

Figure 4 is an elevation of the switch showing the cover elevated to permit of access to the switch;

Figure 5 is a view similar to Figure 1 35 showing the switch button and associated mechanism in depressed position;

Figure 6 is a bottom plan view of the switch mechanism;

Figure 7 is a perspective of the switch 40 plunger and contact members;

Figure 8 is a section on the line 8—8 of Figure 2;

Figure 9 is a wiring diagram showing the 45 switch on the dash board of a car in position to burn the lights brightly with the operating plunger of the dimming switch up, at which time the lights are bright;

Figure 10 is a similar view showing the dimming switch in depressed position and 50 the lights dim;

Figure 11 is a view similar to Figure 9 55 save that the night lights are normally dim because the switch on the dash board is thrown into dimming position;

Figure 12 is a similar view to Figure 11 55 with the switch plunger depressed so that the lights are bright;

Figure 13 is an elevation of the switch with the cover removed showing the plunger in its uppermost position and the contact 60 fingers on the other side from that side shown in Figure 1; and

Figure 14 is a similar view to that shown in Figure 13, showing the plunger depressed.

Referring to the drawings in detail, 1 is the floor board of a vehicle which is constructed to receive the supporting screws 2, the lower ends of which are threaded through the cover plate 3, which has a supporting cup 4. A U-shaped sliding cover 5 closes the open sides of the supporting cup and has its top resting on top of the cover plate 3, an aperture 6 being provided in the sliding cover 5 to permit of the passage of 75 the stem 7, which carries the foot button 8 on the upper end thereof. This button is detachable and the stem itself is adapted to be extended in sections.

The supporting cup 4 carries on its base 80 a plate of insulating material 9 which is provided with depressed grooves 10 for receiving the flat base 11 of the several contact fingers. These bases of the contact fingers are limited in their inward position 85 by a square portion 12 in the center of which is a plunger aperture 13. 14 is the base plate. The bases of the spring fingers are held in position by the screws 15 which constitute the terminal screws which carry on 90 their outside ends below the supporting cup the usual washers 16, nuts 17 and locking washers 18 for clamping the cables thereto. Surrounding the stem 7 is a helical spring 19, one end of which rests on the cup 4 while 95 the other end abuts against the insulated plunger 20, which carries a plurality of segmental contact rings 21, 23 and 25 disposed at different elevations and on different portions of the periphery of this insulated 100 plunger 20.

As will be seen in Figures 1, 2, 4 and 5, the contact fingers 22 and 22' both engage the segmental contact ring 23 when that ring and the plunger are in their uppermost position. The insulated plunger with its contact rings is caused to move downwardly by the foot of the operator and is

limited on its return or upward movement by the cotter pin 24 passing through the stem 7 just above the insulated plunger 20. The contact ring 23 is slotted to receive 5 the contact finger 22^a which always remains in engagement with it. Upon the depression of the insulated plunger 20, as in Figure 5, it will be noted that the contact ring 23 remains in engagement with the finger 10 22^a, but becomes dis-engaged from the finger 22. The finger 22 engages the segmental contact ring 25. This segmental ring 25 extends around the other side of the insulated plunger 20 where it is adapted to 15 engage with a contact finger 26 when the plunger is depressed. The segmental ring 25 extends in the other direction around to the other side of the insulated plunger 20 where it is adapted to engage with the contact finger 27 when the plunger is depressed.

When the insulated plunger 20 is in its elevated position, as in Figure 13, showing its other side of the switch, the contact ring 21 is in engagement with the fingers 26 and 25 20, and, in Figure 14, it is dis-engaged but the depression of the plunger has connected with fingers 26 and 27 the rings 25 and 23 respectively, so that the fingers 26 and 22 are both in engagement with the ring 25 30 when the plunger is depressed and fingers 27 and 22^a are in engagement with the ring 23 when the plunger is depressed.

Referring to the electrical diagram, 29 is a ground for the wire 30 which is connected 35 to a battery 31. This battery is connected by the wire 32 to the switch terminal 33 on which is pivoted a switch arm 34 adapted to engage with the contact 35. This contact is connected by the wire 36 to the 40 spring finger of the switch, designated 22^a, in the position shown. This finger is connected by the contact ring 23 to the contact finger 22, which is, in turn, connected by the wire 37 which, in turn, is connected 45 to the wire 38 and is connected to the bright lamp 39. On its other side, it is connected by the wire 40 to the other bright lamp 41. Each of the lamps is grounded by the grounds 42 and 43.

50 The other side of the circuit is provided with a contact 44 from which leads a wire 45 to the contact finger 26. The other contact finger 27 is connected by a wire 46 to the small or dim lamps 47. In these diagrams the heavy lines indicate the contact rings.

Thus, in Figure 9, the ground 29, wire 30, battery 31, wire 32, terminal 33, switch arm 34, contact 35, wire 36, contact finger 60 22^a, contact ring 23, contact finger 22, wire 37, wires 38 and 40, bright lamps 39 and 41 and grounds 42 and 43 are in circuit.

In Figure 10, the lights are dim because the circuit consists of the ground 29, wire 65 30, battery 31, wire 32, terminal 33, switch

arm 34, contact 35, wire 36, contact finger 22^a, contact ring 23, contact finger 27, wire 46, dim lamps 47 and grounds 42 and 43.

In Figure 11, which lights are normally dim, the circuit consists of ground 29, 70 wire 30, battery 31, wire 32, terminal 33, switch arm 34, contact 44, wire 45, contact finger 26, contact ring 21, contact finger 27, wire 46, lamps 47 and grounds 42 and 43.

In Figure 12, the circuit consists of 75 ground 29, wire 30, battery 31, wire 32, terminal 33, switch arm 34, contact 44, wire 45, contact finger 26, contact ring 25, contact finger 22, wire 37, wires 38 and 40 to lamps 39 and 41 and grounds 42 and 43.

It will be obvious that if the operator throws his switch existing on the car for bright lights, he may cause the lights to be dimmed by depressing the stem and insulated plunger of the foot switch, but, if he carries his lights normally dim with his switch in that position, as in Figures 11 and 12, he can brighten his lights by depressing the stem and insulated plunger of the foot switch.

When I refer to bright and dim, I include filaments of same intensity but so located that one in focus will throw the light a greater distance than the one out of focus. Such terms as bright and dim will be so understood in the claims.

It will be understood that I desire to comprehend within my invention such modifications as may be necessary to adapt it to varying conditions and uses.

Having thus fully described my invention, what I claim as new and desire to secure by Letters Patent, is:

1. In combination, an electrical circuit 105 consisting of a source of current, a plurality of filaments, a portion of which are adapted to be bright and a portion of which are adapted to be dim, a ground for said source of current and a ground for said filaments and a pair of switches located in said circuit, one of which is adapted to connect the source of current either to the bright filaments or the dim filaments, and the other of which switches is adapted when it is actuated, to reverse the connection of the source 110 of current to the respective filaments without disturbing the first mentioned switch, whereby if the first mentioned switch connects the bright filaments, the actuation of the second switch will disconnect the bright filaments and connect the dim filaments, and if the first switch connects the dim filaments to the source of current, the second switch will, upon being actuated, connect the bright filament and disconnect the dim filament. 115

2. In combination, a source of current, a first and second operative position hand switch, a first and second operative position foot switch, bright bulbs and dim bulbs, means for energizing the bright bulbs 120 125

- through the hand-operated switch while it is in the first position and through the foot switch while it is in the first position, and means for energizing the dim bulbs from the 5 source through the hand switch while it is in the first position and through the foot switch while it is in the second position.
3. In combination, a source of current, a first and second operative position hand 10 switch, a first and second operative position foot switch, bright bulbs and dim bulbs, means for energizing the bright bulbs through the hand switch while it is in the second position and through the foot switch 15 while it is in the second position, and means for energizing the dim bulbs from the source through the hand switch while it is in the second position and through the foot switch while it is in the first position.
- 20 4. In combination, a source of current, a first and second position hand switch, a first and second position foot switch, bright bulbs and dim bulbs, means for energizing the bright bulbs through the hand switch while 25 it is in the first position, and through the foot switch while it is in the first position, and means for energizing the dim bulbs from the source through the hand switch while it is in the second position and through the foot switch while it is in the first position.
- 30 5. In combination, a source of current, a
- first and second position hand switch, a first and second position foot switch, bright bulbs and dim bulbs, means for energizing the bright bulbs through the hand switch while it is in the second position and through the foot switch while it is in the first position, and means for energizing the dim bulbs from the source through the hand switch while it is in the second position and through the foot switch while it is in the first position, and means for energizing the dim bulbs from the source through the hand switch while it is in the first position and through the foot switch while it is in the second position.
6. In combination, a source of current, a first and second position hand switch, a first and second position foot switch, means for energizing the bright bulbs from the source 45 through the hand switch while it is in the first position and through the foot switch while it is in the first position, means for energizing the dim bulbs from the source through the hand switch while it is in the 50 second position and through the foot switch while it is in the first position, means for energizing the dim bulbs from the source through the hand switch when it is in the first position and through the foot switch 55 while it is in the second position, and means for energizing the bright bulbs from the source through the hand switch when it is in the second position and through the foot switch when it is in the second position. 60

In testimony whereof I affix my signature.
WILLIAM E. McLAUGHLIN.
